(57) CLAIM

The ornamental design for the ceiling fan blade iron, as shown and described.

DESCRIPTION

FIG. 1 is a perspective view from below of the ceiling fan blade iron in accordance with my design, illustrating the environment of the invention;

FIG. 2 is a bottom plan view of the ceiling fan blade iron in accordance with my design, illustrating the environment of the invention;

FIG. 3 is a side elevation view of the ceiling fan blade iron in accordance with my design, illustrating the environment of the invention;

FIG. 4 is a front elevation view of the ceiling fan blade iron in accordance with my design, illustrating the environment of the invention;

FIG. 5 is an enlarged perspective view from above of the ceiling fan blade iron in accordance with my design, wherein the blade iron has been upturned for illustrative purposes;

FIG. 6 is an enlarged bottom plan view of the ceiling fan blade iron in accordance with my design;

FIG. 7 is an enlarged top plan view of the ceiling fan blade iron in accordance with my design;

FIG. 8 is an enlarged right side view of the ceiling fan blade iron in accordance with my design;

FIG. 9 is an enlarged left side view of the ceiling fan blade iron in accordance with my design;

FIG. 10 is an enlarged front end view of the ceiling fan blade iron in accordance with my design; and,

FIG. 11 is a rear end view of the ceiling fan blade iron in accordance with my design.

The broken line showing of environmental structure in FIGS. 1-4, 6-9 and 11 is for illustrative purposes only and forms no part of the claimed design.
